UNITED STATES PATENT OFFICE

121,541

DESIGN FOR A COMBINED KEY CHAIN AND DRIVER'S LICENSE RECEPTACLE

Joseph G. Lipic, Jr., St. Louis, Mo., assignor to
Jos. Lipic Pen Co., St. Louis, Mo., a corpora-
tion of Missouri

Application March 27, 1940, Serial No. 91,274

Term of patent 14 years

To all whom it may concern:

Be it known that I, Joseph G. Lipic, Jr., a citizen of the United States of America, residing in the city of St. Louis, State of Missouri, have invented a new, original, and ornamental Design for a Combined Key Chain and Driver's License Receptacle, of which the following is a specification, reference being had to the accompanying drawing, forming a part thereof.

Fig. 1 is a perspective view of a combined key chain and driver's license receptacle in a closed position, showing my new design; and

Fig. 2 is a perspective view of the same with the license receptacle in an open position.

The characterizing feature of the invention is that the license receptacle thereof includes a portion having a transparent wall in which portion is displayed a body of liquid or the like.

I claim:

The ornamental design for a combined key chain and driver's license receptacle, as shown and described.

JOSEPH G. LIPIC, JR.
